(57) **CLAIM**

The ornamental design for a ear plug, as shown and described.

DESCRIPTION

FIG. 1.1 is a perspective view of an ear plug;

FIG. 1.2 is another perspective view thereof;

FIG. 1.3 is another perspective view thereof;

FIG. 1.4 is another perspective view thereof;

FIG. 1.5 is a rear view thereof;

FIG. 1.6 is a front view thereof;

FIG. 1.7 is a right side view thereof;

FIG. 1.8 is a left side view thereof;

FIG. 1.9 is a top view thereof; and

FIG. 1.10 is a bottom view thereof.

The broken lines shown in FIGS. 1.1, 1.2, 1.4, and 1.5 illustrate portions of the ear plug that form no part of the claimed design.
